UNITED STATES PATENT OFFICE.

AMOS BARNES, OF PONTIAC, MICHIGAN, ASSIGNOR TO HIMSELF, JAMES BARNES, AND JOSHUA W. BIRD, ALL OF SAME PLACE, ONE-THIRD TO EACH.

PITMAN-CONNECTION.

SPECIFICATION forming part of Letters Patent No. 232,921, dated October 5, 1880.

Application filed August 12, 1880. (No model.)

To all whom it may concern:

Be it known that I, AMOS BARNES, of Pontiac, Oakland county, Michigan, have invented an Improvement in Pitman-Connections for 5 Harvester Cutter-Bars, of which the following is a specification.

The nature of this invention relates to certain new and useful Improvements in the construction of pitman-connections for harvester 10 cutter-bars, whereby the lost motion caused by frictional wear is obviated and placed within the control of the operator.

The invention consists in the peculiar construction, arrangement, and combination of the 15 various parts, all as more fully hereinafter set forth.

Figure 1 is a perspective view of a cutter-bar with my improved pitman attached. Fig. 2 is a similar view, showing the various parts enlarged. Fig. 3 is a vertical section, showing the manner of connecting the pitman with the 20 knife.

In the accompanying drawings, which form a part of this specification, A represents the 25 cutter-bar of a harvester, and B the knife, all of the usual construction. To the heel of the knife B is rigidly secured the stud C, which is recessed upon opposite sides, as shown.

D represents the pitman, which is constructed 30 as follows: a is the push-rod of the pitman, one end of which is properly secured to the wrist-pin b, which is operated by the machine in the ordinary manner. The opposite end of this rod a rests within the recess c, in the rear

face of the stud C. The pull-rod of the pitman consists of two rods, d d'. One end of the rod d is properly secured upon the wrist-pin b, while the outer end of the rod d' is bent in the form of a hook, as shown, and rests within the recess h, in the outer face of the stud C. The 35 two meeting ends of the rods d d' are joined together by means of a swivel-nut, E, the ends of the rods being threaded to receive said nut.

By the use of a pitman constructed substantially as herein described the strain upon the 45 wrist-pin is brought to bear upon opposite sides thereof, and any lost motion that may arise from the frictional wear of the parts is easily taken up by shortening the length of the rods d d' by means of the swivel-nut. 50

What I claim as my invention is—

1. The combination, with the wrist-pin b and stud C, of two independent pitmen, each connected directly and independently of the other to said pin b and stud C, one pushing and the 55 other pulling, substantially as described.

2. The combination of the pin b, stud C, and pitman a, having one end connected directly and independently to the said wrist-pin b and stud C, with the rod d connected directly to 60 the wrist-pin, and rod d' having a hooked end fitting into a recess in said stud C, and connected, by a turn-buckle, E, to the rod d, substantially as and for the purpose specified.

AMOS BARNES.
